UNITED STATES PATENT OFFICE.

JOSEPH CHERNICK, OF NEW YORK, N. Y.

FINGER-RING STRUCTURE.

Application filed March 7, 1928. Serial No. 259,877.

This invention relates to improvements in finger ring structures but especially has to do with novel and unique means whereby the stone, gem, or certain other adornments, may 5 be removed and other jewels substituted at will.

Heretofore it has been the practice to provide mountings for gems wherein the latter are adhesively secured to the ring or similar 10 style of jewelry, and in some instances resilient means is provided for the above purpose. Under these circumstances it is necessary to use special tools in placing or mounting a gem and oftentimes skilled labor is required in this work.

It is therefore the primary object of my invention to provide means whereby a gem or stone of various kinds may be removed from a ring and a new one substituted without the 20 exercise of expert knowledge or the use of special tools.

Another object is to provide a novel ring band embodying a recessed portion wherein a stone may be mounted without danger of 25 accidental displacement thereof during the ordinary usages of a ring.

A still further object of the invention is to provide a novel closure for the stone or gem wherein the latter is protected from injury 30 and whereby said gem is exposed through a top opening.

Still another object is the provision of novel and unique means for securing the gem-closure to a ring band to permit convenient 35 detachment thereof and subsequent disassembling of the component parts.

A still further object is to provide a frame member adapted to cooperate with a gem or stone closure whereby the gem or stone is 40 tightly secured therein.

With these objects in view, together with others which will appear as the description proceeds, the invention resides in the novel formation, combination and arrangement of 45 parts, all as will be described more fully hereinafter, illustrated in the drawings, and particularly pointed out in the claim.

In said drawings:

Figure 1 is an elevation of a ring embodying 50 my invention.

Fig. 2 is a plan view thereof.

Fig. 3 is an elevation of a ring band with the gem or stone closure removed to depict the recess therein.

Fig. 4 is a plan view of Fig. 3.

Fig. 5 is an enlarged sectional view, taken

substantially on the plane of the line 5—5 of Fig. 2, to illustrate the co-relation of certain parts.

Fig. 6 is an elevation showing the several 60 parts detached; and

Fig. 7 is a slightly modified form of ring structure.

Referring now in detail to the accompanying drawings, wherein like characters of reference denote similar parts throughout the several views, let 10 denote the band portion of a ring having its enlarged frontal portion 11 provided with a transverse recess 12, (see Fig. 3), into which is received the gem-closure 13, shown in Fig. 1.

Said gem-closure 13, shown in Figs. 1 to 6 inclusive, is rectangular in form, having an open bottom, and side and end walls, the top thereof having a sight opening 14 bounded by the inturned flanges 15 which partly embrace the marginal top edges of a gem or stone 16 for the obvious purpose of preventing its accidental release from said closure 13.

Upon inspection of Figs. 4 and 6 of the 80 drawings it will be noted that said stone 16 is much thinner than the internal depth of said closure 13 and that I have provided insertible means in the form of a frame 17 whose marginal upper edge receives the basal edges 85 of said stone 16 to position the same within the upper portion of said closure. In view of this construction a relatively thin stone may be used and since the same is concealed from view within the closure the same effect is created as in the case of a relatively 90 heavy or thick stone, which naturally, in its use, increases the cost of the piece of jewelry.

In the assembling of the stone 16, the closure 13 is inverted from the position shown in Fig. 6, whereupon the said stone is dropped therein and the frame 17 inserted to locate the former directly beneath said flanges 15. The parts are now ready for placement within the recess 12 of said frontal portion 11.

Reverting now to the description of the ring band 10, it will be noted upon inspection of Fig. 4 that said frontal portion 11 is provided with an opening 18 leading into said recess 12 and that ears 19 and 20 are provided, the former being apertured, as indicated at 21, Fig. 6, while the latter is provided with a threaded opening 22, (see Fig. 5) for the reception of a set screw 23.

It will also be noted that said closure 13 is 110 provided with a pin 24, (see Figs. 5 and 6), extending from one side wall thereof, whereas

the opposite side wall is supplied with an aperture 25 to be threadedly engaged by said setscrew 23, as will presently appear.

The stone or gem 16 being positioned with-
5 in the closure 13, the assemblage, with the
frame 17 is placed over said recess 12 and the
pin 24 inserted in aperture 21 in said ear 19.
The assemblage is now dropped into said re-
cess 12 and the setscrew 23 applied into said
10 threaded aperture 25 to firmly secure the
parts in the final position indicated in Fig. 5.
It will be noted that the bottom marginal
edge of said frame 17 is flush with the bot-
tom edge of said closure 13 and hence the
15 stone is firmly and tightly held in position.
Also the internal dimension of said frame co-
incides with said opening 18 to provide the
illusion of a continuous opening as in the more
expensive settings.

20 When it is desired to remove the stone, it is
only necessary to partially unscrew said set-
screw 23, whereupon the closure and its asso-
ciated parts may be bodily removed, and a
different stone, or a similar stone, bearing a
25 different letter than that indicated in Fig. 2,
replaced. It is obvious that the sides of the
recess 12 positively cooperates with the aper-
tured ears and setscrew means to maintain
the closure in a fixed position at all times.

30 While the herein disclosure of the idea ap-
pears to present a rectangular closure mem-
ber 13 as the preferred form it will at once be
appreciated that said closure may assume

other shapes, as for instance, oval, or circu-
lar as shown in Fig. 7 of the drawings. In 35
this particular instance the recess will have
arcuate sides 12^a and the side walls of the
closure 13^a will be circularly disposed. In
all other respects the construction is funda-
mentally the same, and hence, while the pres-
ent is a disclosure of the preferred embodi-
ments of the invention, it is to be understood
that the invention is not limited thereto, as
various changes in the minor details of con-
struction, proportion and arrangement of 45
parts may be resorted to without departing
from the spirit of the invention as defined in
the appended claim.

I claim:

A finger ring structure comprising a band 50
including a frontal portion having a recess,
apertured ears located adjacent said recess, a
closure member having top inturned flanges
adapted to be positioned in said recess, a stone
mounted in said closure member, a frame 55
adapted to be inserted within said member
to support said stone and adapted to position
the upper face of the latter against the flanges
of said closure, a pin carried by said closure
and adapted to be received within one of said 60
apertured ears and means associated with the
other apertured ear for detachably securing
said closure within the recess of said frontal
portion.

In testimony whereof I affix my signature.
JOSEPH CHERNICK.
